(57) **CLAIM**

The ornamental design for a firearm hand guard, as shown and described.

DESCRIPTION

FIG. 1 is a perspective view of a firearm hand guard incorporating my new design viewed from in front of, above, and from the left side thereof;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a perspective view a firearm hand guard according to another embodiment incorporating my new design viewed from in front of, above, and from the left side thereof;

FIG. 9 is a front elevation view of the embodiment shown in FIG. 8;

FIG. 10 is a rear elevation view of the embodiment shown in FIG. 8;

FIG. 11 is a right side elevation view of the embodiment shown in FIG. 8;

FIG. 12 is a left side elevation view of the embodiment shown in FIG. 8;

FIG. 13 is a top plan view of the embodiment shown in FIG. 8;

FIG. 14 is a bottom plan view of the embodiment shown in FIG. 8;

FIG. 15 is a perspective view a firearm hand guard according to another embodiment incorporating my new design viewed from in front of, above, and from the left side thereof;

FIG. 16 is a front elevation view of the embodiment shown in FIG. 15;

FIG. 17 is a rear elevation view of the embodiment shown in FIG. 15;

FIG. 18 is a right side elevation view of the embodiment shown in FIG. 15;

FIG. 19 is a left side elevation view of the embodiment shown in FIG. 15;

FIG. 20 is a top plan view of the embodiment shown in FIG. 15; and,

FIG. 21 is a bottom plan view of the embodiment shown in FIG. 15.

The uniform broken lines in FIGS. 1-21 represent environmental structures, such as the barrel of a firearm, and unclaimed portions of the design and the dash-dot lines illustrate boundaries and form no part of the claimed design.
